Atty.

UNITED STATES PATENT OFFICE.

ROBERT F. HALL, OF SCHENECTADY, NEW YORK.

RAILROAD DRAFT APPLIANCE.

Application filed June 14, 1923. Serial No. 645,296.

To all whom it may concern:

Be it known that I, ROBERT F. HALL, of Schenectady, in the county of Schenectady and State of New York, have invented a certain new and useful Improvement in Railroad Draft Appliances, of which improvement the following is a specification.

My invention generally relates to buffer devices of railroad draft appliances, and more particularly to those that are interposed between locomotive engines and their tenders. The object of my invention is to provide a buffer and chafing appliance, to be located between a locomotive and tender, which will permit said vehicles to assume the required relative positions on curved track, without interference or binding of the buffer members, and to accomplish this end by the application of a minimum number of parts. A further object of the invention is to provide means for the compression of the buffer springs, in coupling a locomotive and tender together, which will obviate the necessity of compressing said springs by impact as in prior practice.

The improvement claimed is hereinafter fully set forth.

In a prior and commonly used construction of draft appliances of the general class to which my invention relates, buffers having convex surfaces are provided on both the locomotive and tender, the radii of their adjacent surfaces being struck from the centres of the pins of the draw bar which connects the two vehicles. A floating block, the front and rear surfaces of which are concave, in accordance with the convexity of the surfaces of the locomotive and tender buffers, is interposed between, and fits against said surfaces. One of said last stated buffers is adapted to be capable of adjustment, in the direction of the longitudinal central plane of the vehicle on which it is located, and such adjustment is ordinarily effected by a wedge at the back of the buffer.

A device of the above character institutes a theoretically correct relation between its members for any angular relation of the locomotive and tender, and will allow free movement, if properly adjusted, but it has been found subject to the objection, in practice, that in making adjustment of the wedge, to take up slack in the parts, the workmen frequently carry the adjustment so far that all slack is taken up and the surfaces are brought closely in contact, so that

freedom of movement is lost. This maladjustment results in locking the two vehicles together, preventing their relative movement, and causing undue wear of the flanges of tender truck wheels, as well as other objectionable results.

In a later design of the appliance referred to, springs are applied at the rear of one of the convex faced chafing members, and act to automatically take up slack, without producing undue binding between the adjacent members. This application of springs to the chafing member, imparts to it a capacity for angular movement about a vertical axis, and permits the elimination of the floating block.

In the accompanying drawings: Figure 1 is a plan or top view of the adjoining portions of a locomotive and tender, illustrating an application of my invention; Fig. 2, a vertical longitudinal central section, and Fig. 3, a horizontal section through the buffer of the tender and its case, illustrating a modification of structural detail.

In the practice of my invention, referring descriptively to the specific embodiment thereof which is herein exemplified, and first to Figs. 1 and 2 of the drawings, two railroad vehicles (in the instance illustrated, a locomotive and tender) are connected by a draw bar, 1, the ends of which are fitted on a draw bar pin, 2, on the locomotive, A, and a substantially similar pin, 3, on the tender, B. A chafing block, 4, having a convex outer face, is secured centrally on the rear end of the locomotive, and a buffer, 5, having a concave outer face, the curvature of which is in substantial correspondence with that of the chafing block, 4, is fitted in an open front buffer case, 6, which is bolted, centrally, to the front end of the tender, contact being maintained, in the various relative positions of the two vehicles, between the chafing block and the buffer, throughout the entire extent of the curved face of the latter. The buffer, 5, is held in the case, with the capacity of a limited degree of movement towards and from the rear wall thereof, by a pin, 6*, passing through longitudinal slots in the top and bottom of the case, and bears thereon through helical springs, 7, interposed between it and the rear wall of the case.

In prior constructions of the class to which my invention relates, a convexly curved chafing member has been applied on one

vehicle, bearing on a flat or plane surface buffer on the other. A construction of such character, while admitting of the necessary relative movement of the contacting members on curved track, is subject to the objection that the abutting surfaces of said members have a line contact only, instead of the extended bearing of a surface contact. The provision, in my invention, of 5 a concave bearing surface on the buffer, 5, effects the desirable surface contact, throughout the face of the buffer, and opposes increased lateral resistance to the relative movement of the locomotive and 10 tender on tangent track, correspondingly reducing the effect of lateral vibration, and thereby increasing the steadiness of the running of the two vehicles. As said vehicles assume various relative angular positions on curved track, the buffer moves laterally, relatively to the chafing block, and, at the same time, has an angular movement, 15 relatively to its support, permitted by the interposition of the springs between it and 20 the supporting case.

In the standing, on curved track, adjacent one to the other, of two similar vehicles, having equal bases, their longitudinal central planes intersect in a plane midway 25 between their wheel bases. Inasmuch as the wheel bases of a locomotive and a tender are not of equal length, and are also at unequal distances from their adjacent ends, their central planes, when both vehicles are on a 30 curved track, usually intersect in a plane forward of the connection between them. For a given combination of relative proportions, the position of the plane of intersection will not materially change, within 35 the limits of the radii of curves of the track that are usually met with in railroad service. In the practice of my invention, the radius of the arc of curvature of the abutting surfaces of the chafing block, 4, and 40 buffer, 5, is preferably struck from an axial line, located, as nearly as may be, to the plane of intersection of the central planes of the locomotive and tender. The result of such location is to render the change in 45 compression of the two springs, 7, 7, approximately equal, when the locomotive and tender are both on curved track.

A difficulty is encountered, in practice, in the application of the spring type of buffer, 55 due to the necessity of compressing the springs to their working position, in order to permit of the application of the draw bar pins, 2 and 3, to the draw bar, 1, which couples the locomotive and tender together. 60 This application is sometimes effected by bumping the locomotive and tender together, by another locomotive, thereby compressing the buffer springs by impact. One of the draw bar pins is then dropped into place, 65 the other having been previously inserted,

For obvious reasons, this method of application is objectionable.

In the practice of my invention, referring to Fig. 3 of the drawings, the rear wall of the buffer case, 6, is cut away, so as to allow 70 the springs, 7, 7, to bear directly on the front of the frame, b, of the tender. The parts are assembled, as shown in Fig. 3, and the connecting pin, 6^a, is passed through holes in the top and bottom plates of the 75 case, 6, and through the buffer, 5, thereby connecting the buffer and buffer case, and transferring any load due to compression of the springs, through the buffer to the case. With the springs in their free condition, the 80 side flanges, 6^b, 6^b, of the buffer case will be spaced from the front face of the tender, for a distance equal to the allowance for the desired working or normal compression of the springs. Nuts, 8^a, are then drawn tight 85 on bolts, 8, which pass through the front plate of the tender frame, b, and through the side flanges of the buffer case, thereby bringing said flanges into contact with the tender frame, and compressing the buffer 90 springs, 7, 7, to the desired degree. The locomotive is then moved up to the tender, until the chafing block, 4, comes into contact with the buffer, 5, and the draw bar pins, 2 and 3, are passed through the end 95 eyes of the draw bar, 1, thus connecting the two vehicles. After the insertion of the draw bar pins, the nuts, 8^a, are slackened off, thereby transferring the spring load from 100 the buffer case to the locomotive chafing block, through the buffer. The connecting pin, 6^a, is then withdrawn, and the nuts, 8^a, are drawn up, so as to bring the buffer case side flanges, 6^b, into their normal position 105 of contact with the front of the tender frame. The bolts, 8, and nuts, 8^a, thus serve both to initially compress the springs, 7, and to connect the buffer case to the tender frame.

It is to be understood that the form of 110 construction which is shown in Fig. 3, and hereinbefore described, is applicable, not merely in connection with the specific form of spring buffer which is herein set forth, but also with any other spring buffer construction of the same general type.

I claim as my invention and desire to secure by Letters Patent:

1. In a draft gear for railroad vehicles, the combination of a buffer case, open at 120 its front and rear faces and having laterally extending flanges on its rear face; a buffer slidably mounted in said case and extending through the opening in the front face thereof; springs within the case and extending through the opening in the rear face so as to exert outward pressure on the buffer; a removable pin fixedly connecting the buffer and buffer case; adjusting bolts, fixed to the 125 frame of the vehicle on which the buffer case 130

is supported and passing through said lateral flanges and nuts engaging said adjusting bolts.

2. In a draft gear for railroad vehicles, 5 the combination of a convex block rigidly secured to one vehicle, a concave buffer slidably supported on the other vehicle, springs between the latter and said buffer, a buffer case carried by said latter vehicle so as to

have a fore and aft movement relatively thereto, and a pin to rigidly secure said buffer and case together, and means to draw said case against its vehicle to hold said springs under compression to permit the draw-bar connection between the vehicles to 15 be made, said pin being removable.

ROBERT F. HALL.
